(57) CLAIM

The ornamental design for a plug connection cover, as shown and described.

DESCRIPTION

FIG. 1 is a front elevated view of a plug connection cover showing my new design.

FIG. 2 is a rear elevated view of the plug connection cover.

FIG. 3 is a side elevated view of the plug connection cover.

FIG. 4 is a top plan view of the plug connection cover.

FIG. 5 is a bottom plan view of the plug connection cover; and,

FIG. 6 is a perspective view of the plug connection cover. The broken lines showing the cable throughout the drawing figures are included for the purpose of illustrating environmental structure only and form no part of the claimed design.
